CENTRALIZED TRAFFIC CONTROLLING
SYSTEM FOR RAILROADSWinfred T. Powell, Rochester, N. Y., assignor to
General Railway Signal Company, Rochester,
N. Y.

Application July 21, 1936, Serial No. 91,723

7 Claims. (Cl. 177—353)

This invention relates to centralized traffic controlling systems for governing traffic on railroads and it more particularly pertains to the communication part of such systems.

5 In a centralized traffic controlling system of the type contemplated by this invention, the switches and signals are distributed at field stations throughout the territory and are governed from the control office by means of the transmission of controls over a two-wire line circuit interconnecting the control office with the several field stations. Indications relating to the condition 10 of the switches and signals at the various field stations are transmitted over the same two-wire line circuit to the control office.

The two line wires connecting the control office with all of the field stations in the present embodiment will be referred to as the A line and the B line. These two line wires comprise a single circuit which serves the purpose of carrying the impulses used to select the required station and for transmitting controls to the selected station, as well as serving to carry the indication messages from a transmitting station to the control office for registering a calling station in the office and for transmitting indications from the registered station to the indication signal devices in the office.

The present system is of the coded duplex type, 30 that is, it is operated through cycles of operation for the transmission of controls and/or the transmission of indications during each cycle. When controls are transmitted, a station selecting code is first applied to the line circuit for selecting the desired station and then the controls are transmitted thereto by means of additional coded impulses. When indications are transmitted, the particular field station transmitting first transmits a station registering code 35 for registering or identifying this station in the control office and then the indications from the identified station are transmitted to the control office by means of additional coded impulses.

For the transmission of controls a predetermined number of impulses of selected polarities are placed on the line circuit for operating the apparatus in the control office and at the field stations in synchronism through cycles of operations, irrespective of the polarity of the impulses. 40 The distinctive polarity of the impulses of each series determines the particular station to be selected and the controls to be transmitted thereto.

For the transmission of indications a predetermined number of impulses are placed on the 45 line circuit for operating the apparatus at the

control office and at the field stations in synchronism through a cycle of operations. During a cycle for the transmission of indications alone the apparatus at all field stations and the apparatus at the control office are operated, with the 5 impulses placed on the line circuit being of a non-selecting character so that no station is selected for control during such a cycle.

During an indication cycle the apparatus at the transmitting field station functions to govern 10 the strength of the current which is allowed to flow over the line circuit during its energization and also determines whether a change in the strength of current flowing over the line circuit is effected or not, all for the purpose of 15 making up the indication code.

One feature of the present invention resides 20 in the manner in which a transmitting field station conditions the line circuit during the impulsion of this line circuit for making the impulses of comparatively weak or strong value and also for determining whether or not a weak impulse shall be changed to a strong impulse and whether or not a strong impulse shall be changed 25 into a weak impulse during the impulsion of the line.

Another feature of the present invention resides 30 in the manner in which the apparatus functions for the transmission of controls by means of polar impulses applied to the line circuit, in the same cycle during which this line circuit is conditioned from a transmitting field station for the transmission of indications.

Another feature of the present invention resides 35 in the manner in which the apparatus at all field stations is initiated into operation from the control office. This is accomplished by applying a momentary impulse of alternating current to the line circuit for energizing a start relay at each station. Each start relay is connected to the line circuit in series with a condenser so that the line is normally de-energized, although the control office battery is normally connected to the line circuit for the purpose of 40 conveniently starting a cycle of operations when a field station completes a direct current circuit for this battery.

These characteristics features of the present 50 invention, thus briefly stated will be explained more in detail in the following description of one embodiment and one modification of the invention, while various other characteristic features, functions and advantages of a system embodying this invention will be in part pointed 55

out and in part apparent as the description progresses.

In describing the invention in detail reference will be made to the accompanying drawings, in which those parts having similar features and functions are designated throughout the drawings by like letter reference characters which are generally made distinctive either by reason of distinctive exponents representative of their location in the system, or by reason of preceding numerals representative of their order of operation during a cycle and in which:—

Figs. 1A and 1B (with Fig. 1B placed below Fig. 1A and with correspondingly numbered lines in alignment) illustrate the apparatus and circuit arrangement employed at the control office for providing means whereby the operator may select the stations and govern the switches and signals throughout the territory and also for providing means whereby indications may be received from the various field stations throughout such territory.

Fig. 2 illustrates the apparatus and circuit arrangement employed at a typical field station for providing station selection and the control of a track switch and signals at the selected station, as well as providing for the transmission of indications to the control office.

Fig. 3 illustrates in schematic manner a modification of the indication receiving arrangement in the control office, whereby a vacuum tube detector is provided for detecting the strength of current flowing over the line circuit in accordance with the indications transmitted from a transmitting field station.

For the purpose of simplifying the drawings and facilitating in the explanation, various parts and circuits have been shown diagrammatically and certain conventional illustrations have been employed. The drawings have been made more with the purpose of making it easy to understand the operation of the system rather than with the idea of illustrating the specific arrangement that would preferably be employed in practice. For example, the various relays and their contacts are illustrated in a conventional manner and symbols are used to indicate the connections to the terminals of batteries or other sources of current instead of showing all of the wiring connections to these terminals. Certain relays are shown in Fig. 1B in dotted line blocks to indicate that these are the same relays appearing in Fig. 1A and are connected by dotted lines.

The symbols (+) and (−) are employed to indicate the positive and negative terminals respectively of suitable batteries or other sources of current and the circuits with which these symbols are used always have current flowing in the same direction, that is from (+) to (−). The symbols (B+) and (B−) are employed to indicate the positive and negative terminals respectively of suitable batteries or other sources of current having a mid-tap (CN) and the symbols with which these circuits are used may have current flowing in one direction or the other depending upon whether the terminal (B+) or (B−) is used in combination with tap (CN).

The detailed circuit arrangement and operation of the system may be most readily understood by considering the drawings with Fig. 1B placed below Fig. 1A and with Fig. 2 placed to the right of Fig. 1A.

Control office equipment.—The control office includes a control machine having a group of control levers for each field station, a miniature

track layout corresponding to the actual track layout in the field and various indicating lamps or the like, together with apparatus and circuits to accomplish the desired functions of the system.

For example, the apparatus for one track switch is illustrated as comprising switch machine control lever SML, starting button SB, miniature track switch ts and a track occupancy indicating lamp OS. A signal control lever or levers (not shown) would also be associated with the miniature track switch, but for convenience this apparatus has been omitted since the control of a track switch is considered typical of the control of other types of traffic controlling devices.

The system is started into a cycle of operations by the momentary actuation of starting button SB which stores the start condition by picking up start relay SR, which in turn picks up the corresponding code determining relay CD for determining the code to be transmitted over the line circuit during the following cycle. There is one storing relay and one code determining relay for each station in the system and they are so interlocked that, irrespective of the number of storing relays that are picked up in response to a plurality of actuations of corresponding starting buttons, only one code determining relay for a particular station can be energized during any one cycle of operations.

A neutral line relay F and a neutral line repeating relay FP are provided in the control office for repeating the impulses applied to the line circuit. Slow-acting repeating relays SA and SAP are provided for defining the bounds of an operating cycle, that is, these relays are picked up at the beginning of each cycle and are not dropped out until the end of each cycle.

Associated with the line and line repeating relays is a bank of stepping relays including relays 4V, 2V and 3V, together with a half-step repeating relay VP. These relays are provided to mark off the successive steps of each cycle of operations.

Impulse controlling relay E serves to control the beginning and the end of each impulse period, this relay being operated in response to the step-by-step operations of the stepping relay bank. Relay E controls the operation of polarity determining relays PC and NC, which relays determine the polarity of each impulse applied to the line circuit from line battery LB at each step of the cycle, in accordance with the station selecting code and the controls to be transmitted during the operating cycle.

Message relays 1M and 2M are provided to register the strength of the impulse current permitted to flow over the line circuit and to register whether or not a change in the strength of this impulse current is effective, for the purpose of receiving indications from a transmitting field station. These message receiving relays are so conditioned at each step of the cycle. Resistance RS is provided to compensate for the resistance of the lower winding of relay 1M when this relay is excluded from the line circuit under certain conditions, as will be brought out in the detailed description.

Relay CHI stores whether or not an indication is transmitted by changing the strength of current during each step and controls the executing circuit for this indication condition.

For the purpose of illustrating station registration, pilot relays 1PT, 2PT, 3PT and 4PT are provided. These pilot relays are of the two-position,

polar, magnetic stick type although it will be understood that any suitable type relay may be employed. Indication receiving relays 1IR, 2IR, 3IR and 4IR are also of the two-position, polar, magnetic stick type for storing the indications received from a transmitting field station, which station is registered in the control office by picking up a station relay such as relay ST.

A starting relay STR is provided for initiating the system from a field station at the beginning of a cycle of operations for the transmission of indications. Transformer TF is for the purpose of supplying an initiating impulse of alternating current to the line during the start period of each cycle of operations.

Field station equipment.—The field station illustrated in Fig. 2 is typical of all stations of the system and may be adapted for use at any location by merely connecting certain code jumpers to arrange for the desired codes, but for convenience in the description it is assumed that this is the first station on the line by reason of the distinctive exponents employed.

A track switch TS¹ is illustrated as being operated by a switch machine SM¹, which is in turn controlled by switch machine control relay SMR¹ of the two-position, polar, magnetic stick type, governed from the control office through the medium of the communication system. Suitable signals (not shown) are likewise governed through the medium of the communication system by control relays such as relay SGR¹. The control by this relay has been omitted for the sake of simplifying the present disclosure.

The illustrated track section is contemplated as being of the closed circuit type, with the usual track battery (not shown) and track relay T¹. For the purpose of illustrating the transmission of a number of indications, an additional track relay T² is shown in Fig. 2. Likewise, direction relays RD¹ and LD¹ are shown to illustrate the transmission of a number of additional indications in accordance with the present invention.

The communication part of the system includes a line relay F¹ of the three-position, biased-to-neutral, polar type, together with its quick-acting repeating neutral relay FP¹ and slow-acting relays SA¹ and SAP¹, all for a purpose similar to corresponding relays in the control office.

The field station includes a bank of stepping relays 1V¹, 2V¹, 3V¹ and the half-step relay VP¹, arranged in a similar manner and operating in synchronism with the stepping relay bank in the control office. Since the control of this bank of stepping relays is the same as the control of corresponding relays in the control office the detailed circuits at the field station are omitted, with the control being indicated by the dotted line 101 which connects the impulsing contact 102 of relay FP¹ with the windings of the stepping relays.

For the purpose of illustrating station selection relay SO¹ is shown. This relay is picked up at the beginning of a control cycle and remains up after the transmission of the station selecting code only at the station selected for controls. Line relay F² and slow-acting relay SAP² of the end station are illustrated in the right hand portion of Fig. 2 to indicate how the line circuit is terminated at the station located at the end of the system.

Resistance RS¹ is employed for the purpose of determining the strength of the impulse current

which is permitted to flow over the line circuit as determined by the code provided by the transmitting field station. The inclusion or exclusion of this resistance is controlled by pulsing relays P¹ and P² only at a transmitting field station.

Change relay CH¹ is provided to register a change in any of the traffic controlling devices at the station so that the system will be initiated for the transmission of indications. The operating circuits of this change relay have been omitted but it will be understood that it responds to a change in position of the track relay and the like by means of the momentary de-energization of its stick circuit, in a manner which is disclosed in Patent 1,852,402.

Lock-out relay LO¹ is provided to determine when this field station is to transmit its indications. Whenever the lock-out relay is picked up during a cycle for permitting the associated field station to transmit, pulse relays P¹ and P² are rendered effective to be governed in accordance with the code jumper positions and the positions of the various relays for applying the proper code combination to the line circuit. Impedance IM¹ is connected in series with the upper winding of relay LO¹ and is for the purpose of preventing the flow of sufficient alternating current during the initiating period of a cycle for picking up relay LO¹. By the provision of impedance IM¹ and condenser C¹, the initiating impulse of alternating current is kept out of the winding of relay LO¹ and is caused to energize the winding of starting relay STR¹.

The modification illustrated in Fig. 3 makes use of the same circuits illustrated in the other figures, except that a biasing resistor BR³ is connected in circuit with the line battery LB³ for the purpose of applying a biased potential to the input of vacuum tube VT³ for detecting the strength of the current which is permitted to flow over the line circuit, for operating or not operating message relay M³ in accordance with indications transmitted over the line. Resistance RS³ at the field station corresponds to resistance RS¹ of Fig. 2, except that in the Fig. 3 modification this resistance is removed from the line circuit at a transmitting field station by the picking up of pulse relay P³. When either a code determining relay CD³ or a station start relay STR³ is picked up the primary winding of transformer TF³ is energized for rendering the vacuum tube active.

Operation

The system of the present invention is normally at rest and it may be initiated into a cycle of operations from the control office when new controls are to be transmitted or from a field station when new indications are to be transmitted. In the event that new controls and new indications are ready to be transmitted at the same time at the beginning of a cycle, then the duplex feature of the system permits this transmission simultaneously during the same cycle.

For convenience in describing the operation of the present system, an operating cycle will be divided into a number of impulse periods separated by time spaces and these impulse periods will be referred to as "on" periods of the cycle, with the time spaces between impulses being referred to as "off" periods of the cycle.

Normal conditions.—The normally de-energized line circuit may be energized with direct current by a transmitting field station picking up its lock-out relay for closing up the line cir-

cuit which permits its energization from battery LB in the office. Although the line is normally open to direct current at the end station, the control office may pick up the starting relay at 5 each field station by applying a momentary impulse of alternating current to the line, which is effective to pick up the associated starting relays.

In the control office, code sending relay NC is 10 normally energized over a circuit extending from (+), back contact 10 of relay STR, back contact 11 of relay SA, through all of the back contacts of all CD relays in the CD relay bank, including back contact 12 of the illustrated CD relay, NC 15 bus and winding of relay NC to (-). All other relays in the control office are illustrated as being in their normally de-energized positions.

At the field station, it is assumed that the track section with which track relay T¹ is associated 20 is unoccupied, therefore relay T¹ is normally energized. Change relay CH¹ is normally energized by means of a circuit not shown in the drawings.

Manual start.—For the purpose of considering the operation of the present system for the transmission of controls, it will be assumed that the station illustrated in Fig. 2 corresponds to starting button SB illustrated in Fig. 1A and a detailed explanation will be given of the operation when button SB is actuated for selecting this station. It will be assumed that switch machine lever SML is positioned to the right for controlling the actuation of the track switch illustrated in Fig. 2 to its normal position.

The actuation of button SB closes a circuit for 35 picking up relay SR which extends from (+), contact of button SB and upper winding of relay SR to (-). Relay SR closes a stick circuit for itself extending from (+), front contact 13 and upper winding of relay SR to (-). Assuming that no other SR relay is picked up by the operation of some other starting button, a circuit is closed for picking up relay CD which extends from (+), back contact 14 of relay SA¹, front contact 15 of relay SR, back contact 16 and winding of relay CD to (-). Relay CD closes a stick circuit for itself which extends from (+), front contact 17 of relay SR, front contact 16 and winding of relay CD to (-).

It is assumed that relays SR and CD, associated with the first station in the system, are the first in the series of storing and code determining relays in the bank. The opening of back contact 15 of relay SR interrupts the series pick-up circuit for the other CD relays, which circuit 55 leads to the next SR relay contact similar to contact 15. Therefore, although some other SR relay may be picked up, the circuit for picking up its associated CD relay cannot be energized until the end of the present cycle, when relay SR 60 will be dropped for closing back contact 15 as will be later explained.

It will thus be seen that, by means of this series pick-up circuit, only one CD relay can be picked up at any one time and that one will be the one nearest the live end of the series pick-up circuit extending to back contact 14 of relay SAP. This arrangement permits the storing of a plurality of outgoing calls and the transmission of these calls over the communication system, one at a time in an order determined by the 65 location of the CD relays in the series.

The picking up of relay CD closes a circuit for picking up relay SA which extends from (+), front contact 18 of relay CD, back contacts 19 70 and 20 of relays VP and IV respectively and

winding of relay SA to (-). The picking up of relay SA closes an obvious pick-up circuit for relay SAP at front contact 21.

Since relay SAP is relatively slow in picking up, during the interval between the picking up of 5 relay SA and the picking up of relay SAP, a circuit is closed for energizing the line circuit from the source of alternating current. This circuit extends from the left hand terminal of the upper winding of transformer TF, back contact 22 of 10 relay SAP, front contact 23 of relay SA, B line conductor, back contact 122 of relay SAP¹, upper winding of relay STR¹, condenser C¹, A line conductor, front contact 24 of relay SA and back contact 25 of relay SAP to the right hand terminal 15 of the transformer winding. This momentary application of alternating current to the line circuit is effective to pick up relay STR¹ and since the starting relays at other stations are likewise connected across the line circuit in series 20 with similar condensers, all of these other starting relays will be picked up.

The picking up of relay STR¹ closes a stick circuit for itself extending from (+), back contact 120 of relay SAP¹, front contact 121 and lower 25 winding of relay STR¹ to (-). It will be understood that other starting relays at the other stations close similar stick circuits for themselves.

Referring back to the control office, the picking up of relay SA closes a pick-up circuit for 30 relay E which extends from (+), front contact 21 of relay SA, back contacts 26, 27, 28 and 29 of relays 3V, 2V, IV and VP respectively and winding of relay E to (-). Before relay SA is picked up, normally energized relay NC is dropped 35 because of open back contact 12 of relay CD. After relay E picks up a circuit is closed for picking up relay PC which extends from (+), front contact 30 of relay E, back contacts 31, 32 and 33 of relays 3V, 2V and IV respectively, front contact 34 of relay CD, jumper 35 in its full line position, PC bus and winding of relay PC to (-).

It will be assumed that the station illustrated in Fig. 2 responds to a station selecting code of +—on the first two steps of the cycle. Therefore 45 the polarity of the first impulse is + as determined by code jumper 35 in its full line position. This circuit arrangement for determining the polarity of each impulse will be explained in detail later.

Referring to the field station, the picking up 50 of relay STR¹ closes a circuit for picking up relay SO¹ which extends from (CN), back contact 110 of relay SA¹, front contact 111 of relay STR¹ and upper winding of relay SO¹ to (B—). It 55 will be understood that the SO relays at all other stations are picked up over similar circuits.

The picking up of relay STR¹ closes a circuit for picking up relay SA¹ which extends from (+), front contact 112 of relay STR¹ and winding of relay SA¹ to (-). During the impulsive 60 of the line circuit, relay FP¹ intermittently closes an energizing circuit for relay SA¹ at front contact 100 and this intermittent closure is at such a rate that relay SA¹ does not have time to drop 65 between impulses. As long as relay SA¹ is picked up an energizing circuit is closed for relay SAP¹ at front contact 103. The picking up of relay SA¹ closes a stick circuit for relay SO¹ which extends from (CN), front contact 110 of relay SA¹, front contact 104 of relay SO¹, back contact 105 of relay FP¹ and upper winding of relay SO¹ to (B—). Before this stick circuit is opened 70 at back contact 105 of relay FP¹ during impulsive, a selecting stick circuit is completed for main- 75

taining relay SO^1 energized in accordance with the code applied to the line circuit and repeated by relay F^1 . This selecting stick circuit will be explained later.

It will be understood that similar circuits are closed at all other stations for picking up the associated SA and SAP relays. The picking up of relay SAP² at the end station completes the continuity of the line circuit for direct current at front contact 200. The picking up of the SAP relays drop the STR relays by reason of open back contacts such as 120 of relay SAP¹.

It will be noted that, when alternating current is applied to the line at the beginning of the cycle as just described, the line relays at the field stations are not included in the line circuit. This is because they are normally short-circuited by circuits similar to that illustrated in Fig. 2 which includes back contact 106 of relay SAP¹. This is to prevent the undesired operation of the line relay contacts during the application of the initiating alternating current impulse. This alternating current impulse is terminated when relay SAP in the control office picks up and opens back contacts 22 and 25.

The picking up of relay SAP² at the end station marks the beginning of the first "on" period, since the line is now energized by direct current over a circuit extending from the (+) terminal of battery LB in the control office, back contacts 36, 37, 38 and 39 of relays VP, 1V, 2V and 3V respectively, lower winding of relay 1M, front contact 49 of relay PC, back contact 41 of relay NC, winding of relay F, front contacts 25 and 24 of relays SAP and SA respectively, A line conductor, winding of relay F¹, back contacts 107 and 108 of relays P¹ and P² respectively, winding of relay F², front contact 200 of relay SAP², front contact 122 of relay SAP¹, B line conductor, front contacts 23 and 22 of relays SA and SAP respectively, back contact 42 of relay NC, front contact 43 of relay PC and winding of relay 2M to the (-) terminal of battery LB. It will be understood that the line relays at all stations connected to the system are included in the above described line circuit, so that positive current flowing over this circuit picks up relay F in the control office and positions the polar contacts of the station line relays to the right.

A circuit is closed for picking up relay FP which extends from (+), front contact 44 of relay F, front contact 45 of relay SA and winding of relay FP to (-). A circuit is closed for picking up relay FP¹ which extends from (+), contact 109 of relay F¹ in its right hand dotted position and winding of relay FP¹ to (-).

Polarity selection of impulses.—Whenever the system is initiated from the control office, the first impulse (following the alternating current initiating impulse) applied to the line circuit is determined by the position of code jumper 35 and with this jumper in its full line position the first impulse is + as previously described.

In the event that code jumper 35 is in its alternate dotted line position, then relay NC is picked up during the initiating period for making the first impulse — due to pole changing contacts 40, 41, 42 and 43. It will be later described that relay VP is picked up during the first "on" period, relay 1V is picked up during the first "off" period, relay VP is dropped during the second "on" period, relay 2V is picked up during the second "off" period, relay VP is picked up during the third "on" period, relay 3V is picked up during the third "off" period and relay VP is dropped

during the fourth "on" period. Furthermore, it will be later described that relay E is dropped to terminate each "on" period and is picked up to terminate each "off" period.

With relay 1V picked up during the first "off" period, a circuit is closed for picking up relay NC which extends from (+), front contact 30 of relay E, back contacts 31 and 32 of relays 3V and 2V respectively, front contact 33 of relay 1V, front contact 46 of relay CD, code jumper 47 in its full line position, NC bus and winding of relay NC to (-). It will be understood that the dropping of relay E at the end of each "on" period opens the above described circuit at front contact 30, so that the PC relay or the NC relay (whichever is up) is dropped to de-energize the line circuit. With jumper 47 in its alternate dotted line position, the above described circuit extends by way of the PC bus for picking up relay PC. It will be noted that the control of the PC and NC relays is effected upon the picking up of the stepping relay during the "off" period, so that the next "on" period is started by the picking up of relay E in response to a stepping relay operation. The detailed circuit for controlling relay E will be described later.

After the first two impulses are applied to the line circuit in accordance with the positions of jumpers 35 and 47, relay PC is picked up over a circuit extending from (+), front contact 30 of relay E, back contact 31 of relay 3V, front contact 32 of relay 2V, front contact 48 of relay CD, lever SML in its right hand position, PC bus and winding of relay PC to (-). This determines that the third impulse will be (+) in accordance with lever SML in its normal position. In the event that lever SML is in its reverse dotted line position, then relay NC is picked up for making the third impulse (-).

This operation occurs on each step of the cycle, that is, during the first part of each cycle of operations the code buses determine the code applied to the line for selecting the desired station and during the latter part of the operating cycle the code buses are energized in accordance with the positions of the control levers for transmitting the proper controls to the selected station.

It has been explained how the PC and NC relays are selectively energized in accordance with the position of lever SML. In a similar manner front contact 31 of relay 3V extends through front contact 49 of relay CD for selectively energizing the PC and NC relays in accordance with a signal control lever or the like.

From the above it will be seen that the impulses applied to the line circuit always begin with a short application of alternating current at the start of a control cycle, while the following impulses are of positive or negative direct current depending upon the code jumpers and control levers rendered effective by the particular code determining relay which is picked up for that particular cycle.

Impulsing and stepping relay operations.—Irrespective of the polarity with which the line circuit is energized, the line relays energize the line repeating relays each time the line circuit is energized. At the beginning of the first "on" period a circuit is closed for picking up relay VP in the control office which extends from (+), front contact 50 of relay SA, front contact 51 of relay FP, back contact 52 of relay 1V and winding of relay VP to (-). The picking up of relay VP closes a first stick circuit for itself extending from (+), front contact 50 of relay SA, front contact 53 of

- relay VP, back contact 52 of relay 1V and winding of relay VP to (-).
- When relay FP is dropped during the first "off" period, a circuit is closed for picking up relay 1V which extends from (+), front contact 54 of relay SA, back contact 55 of relay FP, front contact 56 of relay VP, back contact 57 of relay 2V and winding of relay 1V to (-). Relay 1V closes a stick circuit for itself which extends from (+), front contact 54 of relay SA, front contact 58 and winding of relay 1V to (-). It will be pointed out at this time that relays 2V and 3V close similar stick circuits for themselves when they are picked up at front contacts 59 and 60.
- When relay FP is dropped during the first "off" period, a second stick circuit is closed for relay VP which extends from (+), front contact 50 of relay SA, back contact 51 of relay FP, front contact 51 and winding of relay VP to (-). When relay FP is picked up during the second "on" period relay VP is dropped because its first stick circuit is open at back contact 52 of relay 1V and its second stick circuit is open at back contact 51 of relay FP.
- Relay 2V is picked up during the second "off" period over a circuit extending from (+), front contact 54 of relay SA, back contact 55 of relay FP, back contact 56 of relay VP, back contact 62 of relay 3V, front contact 63 of relay 1V and winding of relay 2V to (-).
- The picking up of relay FP during the third "on" period closes a circuit for picking up relay VP which extends from (+), front contact 50 of relay SA, front contact 51 of relay FP, back contact 64 of relay 3V, front contact 65 of relay 2V and winding of relay VP to (-). Relay VP establishes its first stick circuit, which is the same as previously described except that it now extends through back contact 64 and front contact 65.
- When relay FP drops during the third "off" period the above described second stick circuit for relay VP is completed and a pick-up circuit for 3V is established which extends from (+), front contact 54 of relay SA, back contact 55 of relay FP, front contact 56 of relay VP, front contact 57 of relay 2V and winding of relay 3V to (-).
- The picking up of relay FP during the fourth "on" period de-energizes relay VP because its first stick circuit is open at back contact 64 of relay 3V and its second stick circuit is open at back contact 51 of relay FP.
- Since the fourth impulse is the last one of the cycle the next de-energization of the line is effective to return the system to normal. This is because when relays E and PC (or NC) are dropped to de-energize the line at the end of the fourth "on" period there is no other stepping relay to be picked up for changing the circuit condition for again picking up relay E. This effects the de-energization of relay SA because front contact 66 of relay FP is maintained open for a sufficiently long interval of time to allow relay SA to drop. It will be noted that the energization of relay SA is dependent on front contact 66 after relay VP picks up and opens its back contact 19. The dropping of relay SA de-energizes the stick circuits for the half-step and stepping relays at open front contacts 50 and 54.
- It will be understood that this circuit arrangement may be extended for as many steps as desired, with stepping relays being picked up during the "off" periods and the VP relay being shifted during the "on" periods. Since the operation of the stepping relays at the field stations is the same as described in connection with the control office, a description of this function will be omitted. It will be noted in Fig. 2, that contacts 113 and 102 of relays SA¹ and FP¹ respectively are shown leading to dotted line 101 which indicates the control of the stepping relay bank.
- The picking up of relay VP during the first "on" period deenergizes the above described circuit for relay E at back contact 29, which allows relay E to drop and by deenergizing the selected PC or NC relay the first "on" period is terminated, after which relay 1V is picked up.
- The picking up of relay 1V during the first "off" period closes a circuit for picking up relay E which extends from (+), front contact 21 of relay SA, back contacts 26 and 27 of relays 3V and 2V respectively, front contact 28 of relay 1V, front contact 29 of relay VP and winding of relay E, to (-).
- When relay VP drops during the second "on" period, relay E is deenergized because of open front contact 29.
- When relay 2V picks up during the second "off" period, relay E is again energized over the above described circuit which now extends through front contact 27 of relay 2V and back contact 29 of relay VP.
- The picking up of relay VP during the third "on" period opens the energizing circuit for relay E at back contact 29 and relay E is dropped to terminate the third "on" period.
- When relay 3V is picked up during the third "off" period, the above described circuit for picking up relay E is completed, but which now extends through front contact 26 of relay 3V and front contact 29 of relay VP.
- When relay VP drops during the fourth "on" period, relay E is de-energized because of open front contact 29 and, as above described, since there is no other stepping relay to be picked up relay E remains down to terminate the cycle.
- It will be noted that stick circuits are provided for relays PC and NC including their front contacts 67 and 68. These stick circuits are for the purpose of sticking the selected PC or NC relay until relay E drops to mark the end of the fourth "on" period. Since the pick-up circuits for the PC and NC relays include front contacts of the CD relay and since the CD relay is dropped out during the fourth "on" period, these stick circuits prevent the premature de-energization of the line circuit by the dropping out of the CD relays.
- During the fourth "on" period, relay SR is de-energized when relay VP is dropped, by means of a circuit which extends from (+), front contact 18 of relay CD, back contact 19 of relay VP, front contact 20 of relay 1V, front contact 70 of relay 3V, front contact 69 of relay CD, front contact 71 and lower winding of relay SR to (-). Since the energization of the lower winding of relay SR is in opposition to that of its upper winding, this relay will be kicked down. The dropping of relay SR and the consequent opening of its front contact 17 de-energizes the above described stick circuit for relay CD which allows this relay to release.
- Station selection for controls.*—When controls are to be transmitted the field stations are selected one at a time in accordance with the combination of + and - impulses applied to the line circuit during the first or station selection part of the cycle. As above pointed out, each impulse applied to the line circuit causes the step-by-step mechanism at the control office and at each field station to take one step irrespective of the

polarity of the impulse. Since the polarity of each impulse may be either + or -, two steps of the stepping mechanism provide for the transmission of four different code combinations, 5 three steps provide for eight different code combinations and each additional step doubles the number of possible distinctive codes provided. In the present embodiment it is assumed that the 10 number of stations is such that they may be selected on two steps of the cycle.

The circuits for the field stations are similar, the only difference being in the positions of the station code jumpers illustrated in the upper portion of Fig. 2, which jumpers serve to condition 15 or energize one or the other of two station selection buses, indicated + bus and - bus, in accordance with the code call assigned to that particular station. The transmission of a code call connects a selecting stick circuit of the station selection relay (SO) to one or the other of these station selecting code buses. If the code call transmitted corresponds to the code call assigned to the station, then the selecting stick circuit will be connected to an energized bus for 20 each step. If the transmitted code call does not correspond to the station code call, then this selecting stick circuit will be connected to a de-energized bus at one step thereby causing the corresponding station selecting relay to be de-energized. The station with which communication 25 is established is the one at which the station selecting relay remains energized, all other stations except this one being dropped out during the station selecting part of the cycle.

More specifically, considering the operation of Fig. 2, the first impulse applied to the line circuit was + as previously described, which is effective to close the selecting stick circuit for relay SO¹ during the first "on" period over a circuit extending from (CN), front contact 110 of relay SA¹, front contact 104 of relay SO¹, back contacts 114, 115 and 116 of relays 3V¹, 2V¹ and 1V¹ respectively, code jumper 117 in its full line position, + bus, contact 118 of relay F¹ in its right hand dotted position and upper winding of relay SO¹ to (B-). It will be observed that back contact 105 of relay FP¹ is open at this time, so that the selecting stick circuit for relay SO¹ is dependent upon the above described circuit through 45 jumper 117 only. It will be recalled that relay SO¹ at this station (and similar relays at all other stations) was picked up when relay STR¹ closed its front contact 111 at the beginning of the cycle.

During the first "off" period, relay F¹ restores its contacts to their neutral positions and a stick circuit is closed for relay SO¹ which extends from (CN), front contact 110 of relay SA¹, front contact 104 of relay SO¹, make-before-break contact 60 118 of relay F¹ and upper winding of relay SO¹ to (B-). When relay FP¹ drops, the closure of back contact 105 shunts the above described circuit through contact 118. The purpose of contact 118 is to make up this stick circuit before the 65 selecting stick circuit is broken at the time relay F¹ is dropped out. The purpose of contact 105 is to maintain this stick circuit complete after relay F¹ is picked up during an "on" period until the selecting stick circuit is established.

During the second "on" period, the selecting stick circuit for relay SO¹ is closed and extends from (CN), front contact 110 of relay SA¹, front contact 104 of relay SO¹, back contacts 114 and 115 of relays 3V¹ and 2V¹ respectively, front contact 116 of relay 1V¹, code jumper 119 in its full

line position -bus, contact 118 of relay F¹ in its left hand dotted position (because the second impulse is - as previously described) and upper winding of relay SO¹ to (B-).

It will thus be seen that the selecting stick 5 circuit for relay SO¹ is energized or de-energized during each "on" period, depending upon whether the polarity of the received impulse connects this selecting stick circuit to the particular + or - bus which is energized in accordance with the 10 code jumper connections. During each "off" period following an "on" period during which the selecting stick circuit is energized, relay SO¹ is maintained energized over the stick circuit including contact 118 of relay F¹ in its neutral 15 position and in multiple with back contact 105 of relay FP¹.

One-half of the stations have their code jumpers corresponding to jumper 117 connected in an active position while the other half have 20 these code jumpers connected in inactive positions. Thus with the first impulse +, half of the stations will be selected by maintaining the SO relays energized at these stations, while if the first impulse is -, the other half of the 25 stations will be selected by maintaining the SO relays at these stations energized. This selection continues throughout the station selection steps for as many steps required, until the station selecting relay is energized at only one station, 30 which is the station that will receive the control impulses.

The transmission of indications and the registration of a station in the control office during a cycle when no controls are transmitted, which 35 will be later described, is effective to transmit a combination of all - impulses from the control office for operating the stepping relay banks at the various stations in synchronism with the stepping relay bank in the control office. This 40 combination of - impulses is due to the fact that no CD relay in the office is picked up and the circuit through the back contacts of all CD relays, including back contact 12, is extended to relay NC at each step of the cycle 45 for providing a - impulse. This corresponds to a phantom control code which is not assigned to any station, so that the transmission of such a code is not effective to select a station for the transmission of controls when the system 50 is operating through a cycle for the transmission of indications alone. This of course means that one combination out of the possible number of codes cannot be used for station selection, therefore with the provision of two steps, although 55 four separate code combinations are available only three are used for station selection.

Transmission of controls.—Assuming that the proper code combination is applied to the line circuit for selecting the station illustrated in 60 Fig. 2, then upon the application of the third impulse to the line circuit the switch machine control relay SMR¹ is energized from (B+) or (B-) depending upon the character of the impulse applied to the line circuit. With lever 65 SML in its right hand position a + impulse is applied to the line circuit and a circuit is closed for energizing relay SMR¹ in such a direction that its polar contact will be actuated to the right, which circuit extends from (CN), front 70 contact 110 of relay SA¹, front contact 104 of relay SO¹, back contact 114 of relay 3V¹, front contact 115 of relay 2V¹, winding of relay SMR¹, front contact 123 of relay SO¹ and contact 124 of relay F¹ in its right hand dotted position 75

to (B-). In the event that lever SML is in its left hand dotted position, then a — impulse is applied to the line circuit, which positions contact 124 to the left for reversing the current flow through the winding of relay SMR, which is effective to position its polar contact to the left. Polar contact 125 of relay SMR¹ thus assumes a position corresponding to the contact of lever SML for actuating the switch machine to normal or reverse positions over local circuits which are not shown but which are obvious.

In a similar manner any number of additional steps may be provided for transmitting additional controls to the selected field station for governing signals and such other devices as may be employed.

When relay 2V¹ is picked up during the second "off" period, the station selection operation has been completed and therefore a permanent stick circuit is closed for maintaining relay SO¹ energized throughout the remainder of the cycle, which extends from (+), front contact 126 of relay 2V¹, front contact 127 and lower winding of relay SO¹ to (-).

It has already been explained how the relays in the control office are deenergized at the end of the cycle and also most of the relays at the illustrated field station. Relay SO¹ is deenergized at the end of the cycle when relay 2V¹ drops and opens its front contact 126 and as previously described relay 2V¹ is deenergized by the release of relay SA¹.

Transmission of indications.—Although the system is of the coded duplex type arranged for the transmission of indications from any station to the control office during the same cycle that controls are transmitted to the same station or to some other station, it will first be explained how the system operates for the transmission of indications alone on a separate operating cycle. The duplex feature of the system will be explained later in the description. Likewise, the arrangement for allowing the field stations to transmit only one at a time in a predetermined sequence, in the event that there are indications ready for transmission from a plurality of stations at the same time, will be explained in connection with the lock-out feature. It will now be assumed that the station illustrated in Fig. 2 is the only one having new indications ready for transmission.

Automatic start.—A change in the condition of the illustrated track section or a change in the condition of other traffic controlling devices at the illustrated station may occur for de-energizing normally energized change relay CH¹. The dropping of relay CH¹ closes a circuit for energizing the line with direct current, which circuit may be traced from the + terminal of battery LB (control office) back contacts 36, 37, 38 and 39 of relays VP, IV, 2V and 3V respectively, lower winding of relay 1M, back contact 40 of relay PC, front contact 42 of relay NC, back contact 23 of relay SA, B line conductor, back contact 122 of relay SAP¹, impedance IM¹, upper winding of relay LO¹, back contact 128 of relay CH¹, back contact 129 of relay SA¹, A line conductor, back contact 24 of relay SA, winding of relay F, front contact 41 of relay NC, back contact 43 of relay PC and winding of relay 2M to the — terminal of battery LB. The energization of the line circuit effects the picking up of relays F, 1M and 2M in the control office and relay LO¹ at the field

station. The picking up of relays 1M and 2M are ineffective at this time but the picking up of relay F closes a circuit for picking up relay STR which extends from (+), front contact 44 of relay F, back contact 45 of relay SA and upper winding of relay STR to (-). Relay STR closes an obvious stick circuit for itself at its front contact 72.

Relay NC is de-energized because of open back contact 10 of relay STR and relay SA is picked up over a circuit extending from (+), front contact 10 of relay STR, back contacts 19 and 20 of relays VP and IV respectively and winding of relay SA to (-). Relay SA effects the picking up of relay SAP and these slow-acting relays are maintained in their picked up positions by means of the previously described circuits until the end of the cycle. Relay E and the stepping relays function as described in connection with a control cycle for transmitting impulses over the line circuit and for sequentially operating the stepping relay banks. All impulses are — because relay NC is energized to mark the beginning of each "on" period by means of the previously described circuit including front contacts 30 and 11 of relays E and SA respectively and back contact 12 of relay CD.

During the interval between the picking up of relay SA and the picking up of relay SAP, the impulse of alternating current is applied to the line as before, which is effective to pick up the STR relays at the field stations, after which the SA and SAP relays are picked up as previously described. The system now steps through an operating cycle as before and relay LO¹ is stuck up over a circuit extending from (+), front contact 130 of relay SA¹, front contact 131 of relay SAP¹, front contact 132 and lower winding of relay LO¹ to (-). The stick circuit for relay LO¹ is effective as soon as this relay is picked up because back contacts 130 and 131 are then closed and during the interval between the picking up of relay SA¹ and SAP¹ the lock-out feature is effective which will be later described.

Impedance IM¹ connected in series with the upper winding of relay LO¹ is of such a resistance value that it does not interfere with the proper operation of relay LO¹ by direct current applied to the line circuit, but this impedance unit has such an impedance value that the alternating current applied to the line circuit for picking up the starting relays is not effectively shunted by means of the bridge across the line which includes this impedance unit. In other words IM¹ is of low resistance and high impedance. This impedance also serves the purpose of preventing sufficient current from the alternating current source from flowing through the upper winding of relay LO¹ to kick this relay down.

Registration of a field station.—At the particular station (assumed to be the station illustrated in Fig. 2) having indications to transmit, lock out relay LO¹ is maintained energized throughout the cycle as previously explained. Recalling that the stepping relay bank in the control office operates in synchronism with the stepping relay banks at the field stations, it will be noted that the closure of front contacts 133 and 134 of relay LO¹ applies (—) potential to relays P¹ and P² so that these relays will be energized or not in accordance with the condition of the channels selected by the stepping

relay bank. Since no contacts similar to 133 and 134 at any other station are closed, the operation of the stepping relay banks at the other stations is ineffective to condition the associated P¹ and P² relays.

Relays 1M and 2M of Fig. 1A are of the marginal type, being so designed and adjusted that they will pick up in response to a high current flow over the line circuit, but will not be picked up and will be dropped if picked up in response to a low current flow over the line circuit. As will be pointed out in the following description, resistance RS is inserted in the line in place of the lower winding of relay 1M when the step 10 is taken in the office. This is for the purpose of permitting relay 1M to be dropped out when picked up in response to one code transmission in readiness to be picked up or not in response to the next code transmission. Resistance RS 15 has a resistance value approximately the same as the lower winding of relay 1M in order to maintain the value of current flow over the line the same when the winding of relay 1M is excluded from the line as when this winding is 20 included in the line.

For convenience in describing the transmission of indications the indication channels at the field station are divided into two groups, the first group being the strength of the "on" indications, having channels 1¹, 2¹, 3¹ and 4¹ selected in this group. The associated strength of "on" indications group illustrated in Fig. 1B comprises four corresponding indication channels numbered 1, 2, 3 and 4. The second group of 30 indications at the field station comprises channels 5¹, 6¹, 7¹ and 8¹, which are the change of "on" indications. The associated indication channels in Fig. 1B at the control office are the change of "on" indication channels 5, 6, 7 and 8.

40 In accordance with the code jumper connections and the positions of the relay contacts in Fig. 2, the indications transmitted are as follows:—No. 1, high current. No. 5, no change in high current. No. 2, high current. No. 6, a 45 change in the high current. No. 3, low current. No. 7, no change in the low current. No. 4, low current. No. 8, a change in the low current. The above eight indications are transmitted during the four "on" periods of the cycle, with indications 1, 2, 3 and 4 being the strength of the current during the corresponding four "on" periods of the cycle and indications 5, 6, 7 and 8 being the change or no change in the current flowing during the corresponding four 50 "on" periods of the cycle.

No. 1 indication is high current and No. 5 is no change in current. When relay LO¹ is picked up a circuit is closed for picking up relay P¹ which extends from (+), code jumper 135 in its 60 full line position, back contacts 136, 137, 138 and 139 of relays 1V¹, 2V¹, 3V¹ and VP¹ respectively, winding of relay P¹ and front contact 133 of relay LO¹ to (—). Relay P² is picked up at the same time over a circuit extending from (+), back contacts 140, 141, 142 and 143 of relays 1V¹, 2V¹, 3V¹ and VP¹ respectively, winding of relay P² and front contact 134 of relay LO¹ to (—). With relays P¹ and P² picked up, resistance RS¹ is short-circuited by front contacts 107 and 108 so that the line is energized with a high value of current when relay SAP is picked up in the control office, after the application of the alternating current impulse. 70 This effects the picking up of relays 1M and

2M since they are included in the energizing circuit of the line conductor.

When relay VP¹ switches its contact 139 from a back to a front point during the first "on" period, the pick-up circuit of relay P¹ is disconnected with No. 1¹ channel circuit and prepared for the No. 2¹ channel circuit. Since the No. 2¹ channel circuit may or may not be connected to (+) and since the No. 5 indication is no change in current, it is necessary to maintain relays P¹ and P² energized over circuits not including the No. 2¹ channel conductor. Relay P¹ is maintained energized over a stick circuit which extends from (+), back contacts 144, 145 and 146 of relays 3V¹, 2V¹ and 1V¹ respectively, front contact 147 of relay VP¹, front contact 148 of relay P², front contact 149 of relay P¹, winding of relay P¹ and front contact 133 of relay LO¹ to (—). Relay P² is maintained in its picked up position when relay VP¹ picks up because the No. 5¹ channel conductor is connected to (+) in accordance with the No. 5 indication being no change. This circuit extends from (+), jumper 150 in its full line position, back contacts 151, 152 and 153 of relays 1V¹, 2V¹ and 3V¹ respectively, front contact 143 of relay VP¹, winding of relay P² and front contact 134 of relay LO¹ to (—).

Referring to the control office, the No. 1 and No. 5 indications are conditioned during the first "on" period. The No. 1 indication, which is a high current flow over the line circuit resulting in the picking up of relay 1M, is executed when relay VP picks up during the first "on" period by closing a circuit which extends from (B+), front contact 73 of relay 1M, front contact 74 of relay E, front contact 75 of relay VP, back contact 76 of relay 1V and winding of relay 1PT to (CN). This positions the polar contact of relay 1PT to the right. The execution of the No. 1 indication is terminated during the first "on" period when relay E drops and opens the above described circuit at its front contact 74.

Since the No. 5 indication is a no change in current value, as above described, the picking up of relay VP maintains relay 2M in the line circuit 45 because the line circuit is now energized over a circuit which extends from the + terminal of battery LB, front contact 36 of relay VP, back contact 77 of relay 1V, back contact 78 of relay 2V, back contact 79 of relay 3V, resistance RS 50 and over the remainder of the previously described line circuit to the — terminal of battery LB. Relay 2M is maintained picked up during the first "on" period because the current value over the line circuit is maintained high and does 55 not change.

Relay 1M is stuck up after relay VP picks up by means of a circuit extending from (+), back contact 80 of relay 1V, front contact 81 of relay VP, upper winding of relay 1M, front contact 82 of relay 1M and front contact 83 of relay E to (—). When relay E drops to mark the end of the first "on" period, this stick circuit is opened at front contact 83 which effects the release of relay 1M, but since front contact 74 of relay E is 65 opened at the same time, the shifting of contact 73 of relay 1M does not result in the reverse energization of the selected channel circuit.

Relay CHI of Fig. 1B is picked up at the start of the cycle, in response to the picking up of 70 relay SAP, over a circuit which extends from (+), front contact 84 of relay SAP, back contacts 85, 86, 87 and 88 of relays VP, 1V, 2V and 3V respectively and winding of relay CHI to (—). Relay CHI is stuck up over a circuit extending from 75

(+), front contact 84 of relay SAP, contact 90 of relay 2M in either position, front contact 89 and winding of relay CHI to (-).

Since relay 2M is picked up before relay VP is picked up in the first "on" period and since relay 2M does not drop before the termination of this "on" period, relay CHI is maintained stuck up. The No. 5 indication is executed, when relay E drops to mark the end of the first "on" period, by closing a circuit which extends from (B+), front contact 91 of relay CHI, front contact 92 of relay FP, back contact 93 of relay E, back contacts 94, 95 and 96 of relays 3V, 2V and 1V respectively and winding of relay 2PT to (CN). This executing circuit positions the polar contact of relay 2PT to the right. The execution of the No. 5 indication is terminated during the first "off" period when relay FP drops and opens the above described circuit at front contact 92.

20 *High current and change in current indication.*—These indications are typically illustrated by channels 2¹ and 6¹ at the field station and channels 2 and 6 in the control office. When relay 1V¹ picks up during the first "off" period a circuit is closed for picking up relay P¹ which extends from (+), jumper 154 in its full line position, front contact 155 of relay 1V¹, back contacts 156 and 157 of relay 2V¹ and 3V¹ respectively, front contact 139 of relay VP¹, winding of relay P¹ and front contact 133 of relay LO¹ to (-). At this same time relay P² is picked up over a circuit extending from (+), front contact 151 of relay 1V¹, back contacts 152 and 153 of relays 2V¹ and 3V¹ respectively, front contact 143 of relay VP¹, winding of relay P² and front contact 134 of relay LO¹ to (-). The shifting of contact 148 of relay P² makes the energization of relay P¹ dependent on the No. 2¹ channel conductor, because the circuit through front contacts 148 and 147 of relays P² and VP¹ respectively lead to open contact 146 of relays 1V¹.

With relays P¹ and P² picked up, the line is energized with a high current value as before because of closed front contacts 107 and 108. 45 When relay VP¹ drops during the second "on" period the above described pick-up circuit for relay P² is interrupted at front contact 143 and since the No. 6¹ channel conductor is now connected to the winding of relay P², relay P² is de-energized because code jumper 158 is not connected to (+). This results in the dropping of relay P² during the second "on" period and with contacts 107 and 108 out of correspondence, resistance RS¹ is inserted in the line circuit for 50 changing the high current energization to a low current energization.

This change in energization of the line circuit drops relay 2M but relay 1M is maintained picked up for executing the high current code by means 60 of its stick circuit previously described, but it now extends through back contact 81 of relay VP, back contact 97 of relay 2V and front contact 80 of relay 1V. This high current code is executed by energizing the No. 2 channel conductor from (B+) over the above described executing circuit, which now extends through back contact 75 of relay VP, back contact 98 of relay 3V and front contact 99 of relay 1V, to the winding of relay 3PT for positioning the polar contact of this re- 70 lay to the right.

The dropping of relay 2M in response to the change from a high to a low energization of the line circuit momentarily interrupts the stick circuit of relay CHI at contact 90, effecting the 75 release of relay CHI and since its pick-up cir-

cuit is now open at back contact 86 of relay 1V and front contact 87 of relay 2V, it remains down and when relay E is dropped to mark the end of the second "on" period the No. 6 channel conductor is energized over the above described circuit, which now extends from (B-) at back contact 91 of relay CHI and by way of front contact 96 of relay 1V to the winding of relay 4PT for positioning the polar contact of this relay to the left. 10

The above describes the transmission of four codes for effecting the station identification or registration of the typical station illustrated in Fig. 2. This code combination effects the picking up of station relay ST corresponding to the 15 illustrated field station by means of a circuit which extends from (+), front contact 202 of relay 1V, contacts 203, 204, and 205 of relays 1PT, 2PT and 3PT respectively in their right hand positions, contact 206 of relay 4PT in its 20 left hand position and winding of relay ST to (-).

The above four separate indication codes are transmitted during the first two "on" periods of the cycle, with the reception, registration and 25 execution of these codes for station identification explained in detail. It will now be explained how the alternate codes, low current, no change and low current, change are transmitted in accordance with the indications to be transmitted 30 from the identified field station. From this explanation it is believed that it will be obvious how these alternate codes are likewise transmitted in accordance with alternate positions of the code jumpers illustrated in Fig. 2 for identifying other stations in the control office in accordance with these other code combinations. 35

The transmission of the above described code combinations for positioning the four pilot relays as described illustrates that sixteen different code 40 combinations can be transmitted on two steps, fifteen of which can be used for station identification. This is because the four code jumpers illustrated in Fig. 2 can be arranged in sixteen 45 different combinations, but the sixteenth code corresponds to a phantom indication code which must not be effective to register or identify a station in the control office because this code is inherently transmitted during a cycle for the transmission of controls alone, since during such a 50 cycle the line circuit will be energized during the first two "on" periods with high current which is not changed in value. In brief, the code combination of high current, no change during the first "on" period and high current, no change during the second "on" period positions the four pilot relays to positions which do not select a 55 station relay.

It has already been explained how relay CHI in the control office is conditioned by picking it up during the start period so that it may be dropped or not dropped during the first "on" period, as determined by the No. 6 indication being a change or no change respectively in the degree of energization of the line circuit. Relay CHI is conditioned in the first "off" period, the second "off" period and the third "off" period in preparation for being maintained picked up or dropped during the following "on" periods as determined by the 6, 7 and 8 indication codes 60 transmitted. The pick-up circuit for relay CHI during the first "off" period extends through front contacts 84, 85 and 86 of relays SAP, VP and 1V respectively and back contacts 87 and 88 of relays 2V and 3V respectively. The pick-up 65

circuit for relay CHI in the second "off" period is the same except that it now extends through back contact 85 of relay VP and front contact 87 of relay 2V. The pick-up circuit for relay CHI in the third "off" period is the same except that it extends through front contacts 85, 86 and 88 of relays VP, 1V and 3V respectively.

Transmission of indications.—The No. 3 strength of "on" indication is transmitted during the third "on" period as conditioned during the second "off" period. With relay RD¹ down the energizing circuit for relay P¹ is incomplete at open front contact 159 of relay RD¹ so that relay P¹ is not up during the third "on" period. Relay P² is picked up during the second "off" period because the No. 7 indication is no change in the value of the energization of the line circuit, that is the line remains energized at a low value because relay P¹ is not picked up but relay P² is picked up during the second "off" period over a circuit extending from (+), front contact 141 of relay 2V¹, back contact 142 of relay 3V¹, back contact 143 of relay VP¹, winding of relay P² and front contact 134 of relay LO¹ to (—). When relay VP¹ is picked up during the third "on" period this circuit is interrupted but relay P² remains energized over a circuit extending through front contact 143 of relay VP¹, back contact 153 of relay 3V¹, front contact 152 of relay 2V¹ and front contact 160 of relay T¹ to (+). Thus, since contacts 107 and 108 of relays P¹ and P² are out of correspondence during the third "on" period, the third code is low energization of the line and the seventh code is no change in energization of the line.

Relay 1M in the control office is not picked up in response to the low degree of energization of the line circuit and this condition is executed by completing a circuit extending from (B—), back contact 13 of relay 1M, front contact 14 of relay E, front contact 15 of relay VP, front contact 207 of relay 2V, front contact 208 of relay ST and winding of relay 1IR to (CN). This positions the polar contact of relay 1IR to the left. Polar contact 209 of relay 1IR may connect to an indicator lamp (not shown) for indicating that relay RD¹ is deenergized.

The no change indication results in relay 2M remaining down so that the stick circuit of relay CHI is not interrupted, with the result that the No. 7 indication is executed over a circuit extending from (B+), front contact 91 of relay CHI, front contact 92 of relay FP, back contact 93 of relay E, back contact 94 of relay 3V, front contact 95 of relay 2V, front contact 210 of relay ST and winding of relay 2IR to (CN). This positions the polar contact of relay 2IR to the right. Polar contact 219 may control an OS lamp (not shown) for indicating whether or not track relay T¹ is energized.

The No. 4 indication is a low degree of line circuit energization transmitted in the same manner as No. 3, because front contact 161 of relay LD¹ is open for deenergizing relay P¹ when channel circuit 4¹ is closed at front contact 157 of relay 3V¹. Relay P² is picked up during the third "off" period over a circuit extending through front contacts 153 and 143 of relays 3V¹ and VP¹ respectively. When relay VP¹ drops during the fourth "on" period, relay P² is dropped because the No. 8¹ channel circuit selected through back contact 143 of relay VP¹ and front contact 142 of relay 3V¹ is open at front contact 162 of relay T². This results in the low degree of energization of the line circuit being

changed to a high degree of energization because back contacts 107, 108 of relays P¹ and P² both close for short-circuiting resistance RS.

This change from a low to a high degree of line energization takes place during the fourth "on" period at the time the VP relays drop, but before this happens relay 1M is conditioned by remaining down in response to the low degree of energization of the line circuit and when the VP relay in the office picks up this condition of relay 1M is executed by completing an energizing circuit for the No. 4 channel circuit, which circuit now extends through back contact 75 of relay VP, front contact 98 of relay 3V and front contact 211 of relay ST. The dropping of relay VP in the fourth "on" period disconnects the lower winding of relay 1M from the line circuit, since the circuit for energizing the line now extends through back contact 36 of relay VP and front contacts 37, 78 and 39 of relays 1V, 2V and 3V respectively.

The change from a low to a high degree of energization during the fourth "on" period picks up relay 2M in the control office and by means of contact 90 the stick circuit for relay CHI is momentarily interrupted, which allows this relay to release so that the change of "on" indication No. 8 is executed over a circuit extending from (B—), back contact 91 of relay CHI, front contact 92 of relay FP, back contact 93 of relay E, front contact 94 of relay 3V, front contact 212 of relay ST and winding of relay 4IR to (CN). This positions polar contact 213 of relay 4IR to the left which closes an energizing circuit for the OS lamp by way of conductor 9, for lighting this lamp as an indication that track relay T² at the station is down.

From the above examples it is believed obvious how additional indications may be transmitted by providing additional stepping relays in systems of larger size. The above examples illustrate how all eight combinations are transmitted, registered and received and it will be understood that all these combinations may be used for station identification in systems of larger size.

Lock-out between stations.—It may happen that changes occur at more than one station at the same time or in rapid succession, so that more than one station will have new indications to transmit at the beginning of a cycle. In order to prevent more than one station actively associating itself with the communication circuits during the same cycle, lock-out means are provided at each station, effective to select that station nearest the control office having new indications to transmit.

When a change occurs at the first station, illustrated in Fig. 2, the normally deenergized line is momentarily energized from the control office line battery as previously pointed out. When relay NC in the control office drops and when relay SA picks up, the impulse of alternating current is applied to the line for effecting the closure of the line circuit at the end station by relay SAP² closing its front contact 200. The SA¹ relay and the SAP¹ relay at the illustrated station will be picked up in sequence and in the interval between the picking up of relay SA¹ and the picking up of relay SAP¹ the above described stick circuit for relay LO¹ is open, because contacts 130 and 131 of these two relays are out of correspondence.

Relay LO¹ at the first station is maintained energized during this interval from the direct current provided by the control office battery,

over the line circuit by way of the A line conductor, front contact 224 of relay LO¹, back contact 128 of relay CH¹, upper winding of relay LO¹, impedance IM¹ and back contact 122 of relay SAP¹ to the B line conductor. At the station farther out the line having its LO relay picked up, the line circuit is not energized because the B line conductor is open at open front contact 122 of relay SAP¹, open front contact 163 of relay CH¹ and open back contact 164 of relay SA¹. This deenergization of the line circuit extending beyond the first station effects the dropping of the lock-out relay, because the stick circuit for this relay is deenergized by the SA and SAP relays being out of correspondence and because the upper winding of the lock-out relay is deenergized because the B line conductor is open.

After the SAP relays pick up, the continuity 20 of the line circuit is again established but at this time it is too late for a lock-out relay at a more distant station to be picked up because of open back contact similar to contact 122 of relay SAP¹.

25 Since the picking up of the SA relay at a station farther out the line drops the associated lock-out relay after it has been picked up and since the line circuit is not energized after the picking up of the SA relay until the SAP relay is picked up, there is an interval of time during which the lock-out relays at the more distant stations cannot be energized through either winding. From the above it will be noted that the dead line for picking up a lock-out relay 30 is the picking up of the associated SA relay and the consequent opening of its back contact, such as back contact 129 of relay SA¹. As above mentioned, the line cannot be conditioned for indications at a station unless its lock-out relay is picked up and its contacts 133 and 134 are closed.

Although the lock-out feature has been explained with reference to the first station and other stations of the system, it will be understood that similar conditions may exist between various 45 combinations of stations, but it is believed that the explanation given is sufficient for an understanding of all such combinations, remembering that the nearest station to the control office with its lock-out relay picked up before the dead line is reached is a superior station and all others which may be picked up at this time are inferior 50 stations, which will be dropped out when the system passes this dead line.

Front contact 163 of relay CH¹, which bridges back contact 164 of relay SA¹, is for the purpose of preventing a superior station having no indications to transmit interrupting the continuity of the line circuit by opening back contact 164 of its SA relay at the start of a cycle. By bridging contact 164 with front contact 163 the continuity 60 of the line circuit is maintained complete at those stations not having indications to transmit until the SAP relay picks up and closes front contact 122.

65 *Duplex operation.*—It has been pointed out that control and indication cycles may each occur separately or simultaneously. The operations for control cycles alone and the operations for indication cycles alone have been described and 70 it will now be pointed out how the system operates when controls and indications are transmitted during the same cycle.

The actuation of a starting button in the control office picks up its associated storing relay. 75 During the time that the system is at rest and

any time up to the end of the period marked off by the opening of back contact 14 of relay SAP, the CD relay associated with the actuated starting button can be picked up to mark the cycle as one for the transmission of controls. If a field station initiates the system after the SAP relay has been picked up, the control office cannot transmit controls during this cycle because of open back contact 14, but it must wait until the beginning of the next cycle.

On the other hand, a lock-out relay at a field station may be picked up at the beginning of a cycle any time up to the picking up of the associated SA relay and the consequent opening of a back contact similar to 129 of relay SA¹ of Fig. 15. After this contact is picked up the associated field station cannot actively associate itself with the communication circuits until the beginning of another cycle.

Therefore under the condition that the system 20 is initiated by the picking up of a CD relay in the control office and a lock relay at a field station at the beginning of a cycle, both controls and indications can be transmitted during this cycle. The polarity of each impulse applied to the line 25 circuit is determined by the code jumper and lever connections selected by the energized CD relay. The identification or registration of a particular field station for the transmission of indications is determined by the particular lock-out relay 30 which is picked up for effecting the transmission of indication codes as previously described. Since controls are transmitted outward from the control office and since indications are transmitted inward to the control office by the separate and independent conditioning of the two-wire line circuit, these controls and indications may be simultaneously transmitted during the same cycle.

Since the transmission of outbound and inbound messages have been explained in detail for separate cycles of operation and since the line circuit is distinctively conditioned in a separate and distinctive manner for the transmission of both kinds of messages, it is not believed necessary to repeat the detailed description of these transmissions during a duplex cycle.

Modification

It has been explained in connection with the registration of the high and low current impulses 50 by relays 1M and 2M of Fig. 1A, that these relays are so designed and adjusted that they will respond to high current energization but will not respond to low current energization, even though the low current flows through their pick-up windings. In other words, relays 1M and 2M are of the marginal type.

The arrangement disclosed in the Fig. 3 modification provides a means for using one or more message relays for receiving the indications 60 transmitted over the line circuit, which relays are not of the marginal type. This is accomplished by determining the amount of grid bias applied to a vacuum tube, having one or more 65 relays connected in its plate circuit, as illustrated by relay M³ of Fig. 3.

The arrangement is shown in abbreviated form, with the line circuit arrangement of the other figures illustrated somewhat in detail to indicate 70 that this modified circuit may be applied to the previously described transmitting arrangement. The indication transmitting contact at the field station is illustrated as contact 300, operated by impulse relay P³ for short-circuiting resistance 75

RS³ to provide a high degree of line circuit energization.

The PC, NC, SAP and SA relay contacts are illustrated, with these relays having the same reference characters as corresponding relays in the Fig. 1A modification, but with the exponent 3 added. It will be understood that the operation for the transmission of controls and for the transmission of indications is the same as previously described. It will now be explained how the indications are received in the control office.

It will be obvious that a contact may be provided on start relay STR³ and on code determining relay CD³ for controlling the energization of the tube circuits when the system is initiated. This provides heating current for the heater element of the tube and a comparatively high potential for the plate circuit of the tube.

Bias resistor BR³ is connected between the + terminal of line battery BL³ and the grid of the vacuum tube. With this resistor located at this point in the line circuit, + potential connected either to the A line or the B line, in accordance with the operations of relays PC³ and NC³, is applied to the terminal of the bias resistor which connects to the grid.

Assuming that a + control impulse is applied to the A line conductor, current flows from the + terminal of battery LB³, through relays F⁴, F³ and F (at the end station or at other stations connected to the line circuit), returning to the - terminal of battery LB³ by way of the B line conductor and bias resistor BR³. The resistance values of the line relays in the line circuit and the line circuit itself (with resistance RS³ short-circuited), are so related that under this condition the grid of the tube is made sufficiently positive to cause its plate circuit to conduct. Since relay M³ is included in the plate circuit and since the tube will pass current in only one direction, pulsating current is applied to the winding of this relay for picking it up to register a first indication condition.

When a - control impulse is applied to the line circuit, the connection to the line is reversed beyond bias resistor BR³ with respect to the line battery, so that the same polarity occurs at the terminals of the bias resistor BR³ as before.

The other indication condition is transmitted when relay P³ is down to insert resistance RS³ in the line circuit. The inclusion of this resistance in series with resistance BR³ lowers the positive potential applied to the grid of the tube beyond the cut-off point so that the tube is rendered non-conducting. Therefore relay M³ does not receive any current under this condition and with this relay deenergized the second indication condition is registered.

The reason that the grid or detecting circuit of the vacuum tube thus discriminates between the potential existing across the terminals of resistance BR³ under the above described conditions may be stated in this way. By decreasing the value of the resistance in the line circuit (by short-circuiting resistance RS³) more current flows from battery LB³ through resistance BR³, so that the IR drop through resistance BR³ becomes greater, with that terminal of the resistance remote from the - terminal of battery LB³ becoming more positive in potential. Since the grid is connected at this point, its potential becomes more positive with respect to the cathode, which is connected to the - terminal of the battery.

It will be noted that this arrangement differs

materially from the arrangement disclosed in Fig. 1A, in which the marginal relay detects, by picking up or not picking up, the exclusion or inclusion of the resistance at the field station. In other words, the arrangement disclosed in Fig. 3 is a voltage operated device in which a difference in potential brought about by the inclusion of a resistance in the line circuit at the field station is used for controlling the circuit in which the message relay is included, so that this circuit receives current or does not receive current. Therefore, message relay M³ does not need to be marginally adjusted and designed with respect to the circuit in which it operates, but it may be so designed that it responds to current flow of any material value.

Although one specific embodiment and one modification of the invention have been shown, it is to be understood that various rearrangements may be made and still come within the scope of the invention.

Having thus described a centralized traffic controlling system as one specific embodiment of the present invention, it is desired to be understood that this form is selected to facilitate in the disclosure rather than to limit the number of forms which the invention may assume and it is further to be understood that various modifications, adaptations and alterations may be applied to the specific form shown to meet the requirements of practice without in any manner departing from the spirit or scope of the invention except as limited by the appended claims.

What I claim is:

1. In a code transmitter, a line circuit over which codes are transmitted, a pair of relays, means for positioning said relays in corresponding and non-corresponding positions, means including said relays in corresponding positions for transmitting a first code over said line circuit comprising an impulse of current of comparatively high value, and means including said relays in non-corresponding positions for transmitting a second code over said line circuit comprising an impulse of current of comparatively low value.

2. In a code transmitter, a line circuit over which codes are transmitted, a pair of relays, means for positioning said relays in corresponding and non-corresponding positions, means including said relays in corresponding positions for transmitting a first code over said line circuit comprising an impulse of current of comparatively high value, means including said relays in non-corresponding positions for transmitting a second code over said line circuit comprising an impulse of current of comparatively low value, means for changing the position of a first one of said relays during the transmission of either said first or said second code, and means responsive to said change in position of said first relay for transmitting a third code over said line circuit comprising a change in the degree of energization of said line circuit.

3. In an impulse transmitting system, a loop impulse transmitting circuit, means at one end of said loop circuit for generating and transmitting time spaced impulses of current over said circuit, code transmitting means at the other end of said loop circuit, a relay controlled by said code transmitting means for by the position assumed by its contact determining the initial high or low strength of each of said impulses to form codes, and a second relay controlled by said code transmitting means for when operated to either change said current strength from a high to a

low or from a low to a high current strength during subsequent portions of said impulses to form additional codes.

4. A selector system for transmitting distinctive codes over a line circuit from a station to an office comprising, a line circuit connecting said office and said station, means at said office for intermittently energizing said line circuit with a plurality of impulses of normally high current value, means including a first relay at said station for making the first part of each of said impulses of abnormally low current value or leave it at said normally high current value to form a first code, means including a second relay at said station for either changing or leaving unchanged the value of the current during the second part of each of said impulses to form a second code, and code responsive means in said office selectively responsive to said first and said second codes.
5. In a remote control system of the selector type, the combination with a control office and a field station, of a line circuit connecting said office with said station, impulsive means at said office for energizing said line circuit with a plurality of impulses to define a code period, means including a first relay at said station for establishing a current strength of high or low value for each impulse during the first part of each of said impulses to form a code, and means including a second relay at said station for during a second part of each impulse changing said high current to a low current, a low current to a high current or leave unchanged the current strength of said impulses to form a second code.
6. In a remote control system of the character described; the combination with a control office and a field station; a line circuit connecting said office and said station; impulsive means at said

office for energizing said line circuit with a plurality of impulses to define a code sending period; means including a first relay at said station for establishing a current strength of high or low value for each impulse during the first part of such impulse to constitute a plurality of impulses of a code transmitted within said code period; and means including a second relay at said station for during the second part of each impulse changing such impulse from a high or a low value as determined by said first relay to a low or a high value respectively, or for leaving the value of said impulse as determined by said first relay to form a second code.

7. In a remote control system, a line circuit having a plurality of series of time spaced impulses of distinctive strength impressed thereon, a step-by-step mechanism operable through a separate cycle for each of said series, means controlled by said mechanism for selecting two local channel circuits for each step, means for causing said mechanism to take one step for each time space between successive impulses of a series, means including a first relay for at times determining the strength of said impulses during their impression on said line circuit, means including a second relay for at times thereafter changing the strength of the current as determined by the first relay during each of said impulses, means for distinctively energizing one of said channel circuits in accordance with the strength of the impulse impressed in said line circuit for that step, and means for distinctively energizing the other of said channel circuits in accordance with whether there has been a change or no change in the strength of the impulse during that impulse for that step.

WINFRED T. POWELL.
